UNITED STATES PATENT OFFICE.

JAMES M. LEAVER, JR., OF OAKLAND, CALIFORNIA.

AUTOMATIC BUNDLING-MACHINE.

1,260,003.

Specification of Letters Patent. Patented Mar. 19, 1918.

Application filed December 21, 1916. Serial No. 138,228.

To all whom it may concern:

Be it known that I, JAMES M. LEAVER, JR., a citizen of the United States, residing at Oakland, in the county of Alameda and State of California, have invented a new and useful Automatic Bundling-Machine, of which the following is a specification.

The invention relates to an automatic bundling machine.

10 The object of the present invention is to improve the construction of bundling machines, and to provide an efficient and comparatively inexpensive machine, designed for bundling cut lumber and various other materials, and capable of automatic operation to form bundles of uniform size. A further object of the invention is to provide a bundling machine, equipped with mechanism adapted to engage automatically a predetermined number of pieces of material in a magazine and capable of removing them from the bottom of a stack or pile and of presenting them in bundle form at a point beyond the magazine for binding or tying.

25 Another object of the invention is to provide means for supporting the stack or pile in an elevated position during the feeding operation and the return movement of the feeding mechanism, and for lowering the stack to the bottom of the magazine for recharging the machine after the feeding mechanism has returned to its initial position. The invention also has for its object to provide mechanism of this character 30 capable of ready adjustment to vary the size of the bundle and to arrange the parts to suit the length of the material bundled.

With these and other objects in view, the invention consists in the construction and 40 novel combination of parts hereinafter fully described, illustrated in the accompanying drawings, and pointed out in the claims hereto appended.

In the drawings:—

45 Figure 1 is a side elevation of an automatic bundling machine, constructed in accordance with this invention and illustrating the initial positions of the parts.

Fig. 2 is a similar view of the opposite 50 side of the machine, showing the material for forming the bundles advanced slightly from the lower end of the magazine.

Fig. 3 is a central longitudinal sectional view, showing the bundle advanced into the 55 bundle receiving space or chamber and the

feeding mechanism returned to its initial position, the stack of material being supported within the magazine at an elevation.

Fig. 4 is a rear elevation of the machine.

Fig. 5 is a plan view of the machine, parts 60 being removed.

Fig. 6 is a transverse sectional view on the line 6—6 of Fig. 1.

Fig. 7 is an enlarged sectional view on the line 7—7 of Fig. 5.

Fig. 8 is a fragmentary enlarged sectional view on the line 8—8 of Fig. 7.

Fig. 9 is a sectional view on the line 9—9 of Fig. 1, looking in the direction of the arrow.

Fig. 10 is a sectional view on the line 10—10 of Fig. 1, looking in the direction of the arrow.

Fig. 11 is a sectional view on the line 11—11 of Fig. 4, looking in the direction of the arrow.

Like numerals of reference designate corresponding parts in all the figures of the drawings.

The drawings disclose one embodiment of the invention, while the claims define the actual scope thereof.

The accompanying drawings, which illustrate the preferred embodiment of the invention, show an automatic bundling machine designed primarily for use in connection with the automatic binding and tying mechanism, forming the subject-matter of a companion application, but the bundling machine of the present invention is also susceptible of operation in connection with any other preferred form of bundle binding and tying mechanism, and if desired the bundles formed by the machine may be bound and tied by hand.

The main frame of the machine, which may be constructed of any suitable material, is provided at the base with front and rear transversely disposed I-beams 1, which may be either mounted on blocks or sills, or 100 equipped with heavy casters to render the machine portable. The front and rear transverse beams are connected at their ends by side longitudinal beams 2 and 3 at a point between their ends with an intermediate longitudinal beam 4. The side and intermediate longitudinal beams, which preferably consist of I-beams, are seated upon the upper flanges of the bottom transverse beams 1 and are bolted or otherwise secured to the 110

same. The main frame is provided at a point intermediate of the ends of the side beam 3 and the intermediate beam 4 with front vertical columns 5 and at the rear ends of the said beams 3 and 4 with rear vertical columns 6. The front and rear columns, which are bolted or otherwise secured at their lower ends to the upper flanges of the longitudinal beams 3 and 4, support spaced longitudinal beams 7, which are bolted or otherwise secured to the upper ends of the columns 5 and 6. The main frame is stiffened by an inclined transverse brace 8, secured at its lower end to the side longitudinal beam 2 and extending upwardly and inwardly therefrom to the upper longitudinal beam of the adjacent side of the frame and suitably secured at its upper end to the same. The main frame is also stiffened by upper and lower inclined longitudinal braces 9 and 10, arranged in substantially the same inclined plane. The lower inclined brace 9 extends upwardly and rearwardly from the front end of the intermediate longitudinal beam 4, and is secured to the adjacent front column 5 at a point intermediate of the ends thereof, and the upper brace 10 extends upwardly and rearwardly from the central portion of such front column to the underside of the top longitudinal beam 7, and its upper end is secured to the same near the center thereof. The top longitudinal beams 7 are connected at points intermediate of their ends by top transversely disposed I-beams 11, bolted or otherwise secured to the longitudinal beam 7 and located at the front ends thereof and at a point adjacent to the rear ends of the same.

The main frame may, of course, be of any other preferred construction, and the bottom transverse beams 1 and the top transverse beams 11 constitute rails and form transverse tracks for slidably mounting a plurality of laterally adjustable upper and lower auxiliary frames or supports, which carry the mechanism for feeding the bundles. In the accompanying drawings, two laterally adjustable sets of upper and lower auxiliary frames or supports are shown arranged at spaced points at opposite sides of the center of the machine, and these auxiliary frames are adjustable by means of upper and lower right and left hand threaded screws 12 and 13, which, when operated by the means hereinafter described, move the adjustable frames simultaneously toward and from each other. The machine may be equipped with any number of sets of upper and lower auxiliary frames, but when three sets of such frames are employed, one set will be located at the center of the machine and the central set will be stationary and the side sets will be adjustable toward and from the central set of the auxiliary frames or supports. The lower auxiliary frame of

each set is provided at the bottom with spaced longitudinal channeled bars 14 and 15 and at the top with a longitudinal channeled bar 15^a, located above and in substantially the vertical plane of the lower channeled bar 14 and connected with the same at the ends of the lower auxiliary frame by front and rear upright bars 16 and with the ends of the lower channeled bar 15 by inclined transverse braces 17. The lower channeled bars 14 and 15 are connected by transverse rods 18, arranged in pairs and secured to the channeled bars at the inner faces thereof by screws 19, piercing the webs of the channeled bars 14 and 15 and engaging threaded sockets in the ends of the transverse rods 18, but any other suitable means may, of course, be employed for connecting the channeled bars and for maintaining the same in spaced relation.

The longitudinal bars 14 and 15 of the lower auxiliary frames are slidably connected at their front and rear portions with the bottom transverse beams 1 of the main frame by inner stops and outer clamps 20, bolted to the bars 14 and 15 at the lower edges thereof and extending across the space between the same, and each provided with an upper recess 21 to receive the outer upper flange of the contiguous transverse beam 1 and extending beneath the said upper flange and equipped with an adjustable steel plate 22, which is forced into engagement with the lower face of the outer upper flange of the transverse beam by a set screw 23, mounted in a threaded opening 24 in the recessed portion of the clamp 20. The front stop 25, which is spaced from and co-operates with the front clamp, consists of a strip secured to the front portions of the channeled bars 14 and 15 and extending across the space between the same, and the rear stops are preferably formed by spaced transversely aligned bearing blocks 26, secured to the bottom flanges of the bars 14 and 15 at the rear portions thereof. When it is desired to adjust the lower auxiliary frame, the plates of the clamps are loosened by unscrewing the set screws and after the proper adjustment has been made, the set screws are tightened to cause the steel plates to grip firmly the bottom transverse beams of the main frame.

Each upper adjustable auxiliary frame or support is preferably composed of spaced longitudinally disposed angle bars 27, connected at their rear portions by transverse plates or bars 28, which are secured to the horizontal wings or flanges of the angle bars 27 by vertical rods or bolts 29, piercing horizontal wings or flanges of spaced angle bars 30, arranged in pairs at opposite sides of the rear portion of the upper auxiliary frame and forming horizontal guideways. The horizontal wings or flanges of the angle bars

130

30 of the guideways are spaced apart by sleeves 31, and the lower angle bars of the guideways are supported by vertical tubes 32. The sleeves and the tubes are arranged 5 on the vertical rods or bolts 29, and the tubes are supported upon the horizontal flanges of the side angle bars 27 of the upper auxiliary frame and are interposed between the same and the lower angle bars of 10 the superimposed guideway, which extends longitudinally of the said upper auxiliary frame. The side bars of the upper auxiliary frame are also connected at their front ends by a transverse plate or bar 33, having terminal flanges bolted or otherwise secured to 15 the vertical wings or flanges of the side bars 27.

The upper auxiliary frame is slidably supported by the upper transverse main 20 frame beams 11, fitting against the inner edge of the plate or bar 33 and against one of the transverse plates or bars 28 and engaged by adjustable clamps 35. The clamps 35, which are adjustably secured to the lower 25 faces of the bottom flanges of the side bars 27 of the upper auxiliary frame by set screws 36, have recessed engaging portions, which extend beneath the adjacent upper flanges of the transverse beams 11 of the 30 main frame. When the screws 36 are tightened to engage the jaws of the upper transverse beams 11, the upper auxiliary frame is firmly gripped thereon.

The machine is equipped at the front with 35 a vertical magazine 37, adapted to receive a stack 38 of material, which may consist of pieces of cut lumber, or any other material of a similar character, adapted to be handled in bulk and tied in bundles. The 40 magazine, which may be constructed in any desired manner, is illustrated in the accompanying drawings as consisting of outer fixed vertical bars 39 and inner adjustable vertical bars 40, adapted to be moved toward and from the outer fixed vertical bars 45 to vary the size of the magazine. Each set of upper and lower auxiliary frames is 50 equipped with a pair of these magazine forming bars 39 and 40 and the upper longitudinal channelled bars of the lower auxiliary frames constitute the bottom of the magazine. The fixed outer vertical bar 39 is secured at its lower end to the front end of the upper channelled bar 15^a of the lower 55 auxiliary frame, and the inner adjustable bar 40, which is arranged in the same longitudinal plane as the outer fixed bar 39, is provided at its end with a rearwardly extending horizontal arm 41, which is adjustably secured by bolts 42, or other suitable fastening devices to one of the angle bars 27 of the upper auxiliary frame (see Fig. 5). As shown in Figs. 1 to 3 inclusive, the inner vertical magazine bars 40 are arranged at 60 the limit of their rearward movement to

provide a bundle of the maximum width, and they are adapted to be adjusted forwardly from such position to decrease the width of the bundle. The inner adjustable magazine forming bars 40 terminate at the 70 side bars of the upper auxiliary frames to form an opening 43 at the lower portion of the inner or rear side of the magazine 37 to permit the lower portion of the stack 38 to be advanced or moved rearwardly from 75 the magazine into a bundle receiving space or chamber 44. The upper longitudinal channelled bars 15^a of the lower auxiliary frames constitute a support for the material, and the bundle when formed by the feeding 80 mechanism about to be described is movable along the channelled bars 15^a to a point beyond the magazine to the position illustrated in Fig. 3 of the drawings.

The feeding or bundle forming mechanism, which feeds the material from the bottom of the stack, comprises in its construction a lower longitudinally slidable horizontal bar 45, an inner vertical bundle engaging bar 46, a top horizontal stack supporting bar 47, and an outer vertical bar 48 extending upwardly from the outer end of the slidable bar 45 to the outer end of the top stack supporting bar 47. The lower horizontal bar 45, which constitutes the slide, 90 operates in the groove or channel of the top longitudinal bar 15^a, which forms a guide for the said bar 45. The vertical bars 46 and 48 are suitably secured at their upper ends to the horizontal stack supporting bar 100 47, and their lower portions are adjustably connected to the slidable bar 45 by clamping plates 49, secured by bolts 50, or other suitable fastening devices to the bar 45 and adapted to clamp the bars 46 and 48 in vertical adjustment. By this construction the effective length of the bundle forming bar 40 is varied to form a bundle of the desired height, and the stack supporting bar 47 is 105 raised and lowered to arrange it in the proper position for supporting the stack left within the magazine during the feeding of the material in the formation of the bundle.

The inner or rear end of the slidable bar of the feeding device is pivoted to the upper 115 end of an inclined connecting link 51, extending downwardly and rearwardly from the slidable bar 45 and pivoted at its lower end to the upper end of a cam actuated lever 52. The cam actuated lever 52 is of 120 angular form, and when the feeding device is in its initial position, or at the limit of its outward or forward movement, as illustrated in Figs. 1 and 3 of the accompanying drawings, the upper portion of the lever 52 is arranged at an inclination and extends downwardly and rearwardly over a main transverse shaft 53 to a point in rear of the same, and when the lever is in such position, its lower portion, which is arranged at an ob- 125

4

tuse angle to its upper portion, extends downwardly and forwardly to a transverse pivot 54 upon which the lever 52 is mounted. The pivot 54 is arranged in a suitable bearing bracket 55, secured to the channeled bar 14 at the lower web or flange thereof. The transverse pivot 54 is located below and slightly in rear of the main transverse shaft 53, the angular shape of the lever 52 enabling the same to clear the shaft 53 in its backward and forward oscillation. The lever 52 is provided at its angle with a roller 56, which is arranged in a cam groove 57 in the outer face of a cam disk or wheel 58, which when rotated oscillates the lever 52 to reciprocate the feeding device. At each revolution of the cam disk or wheel 58, the feeding device is movable inwardly or rearwardly a sufficient distance to carry the material at the bottom of the stack from the magazine to the bundle receiving space or chamber and is moved forwardly and returned to its initial position. The cam groove 57 consists of similar opposite actuating portions to swing the lever 52, and an intermediate curved connecting portion arranged concentric with the pivot of the cam disk or wheel 58 is adapted to cause the lever 52 to dwell at the inner or rearward limit of its movement while the bundle is being bound and tied when the machine is equipped with such mechanism. The upper portion of the lever 52 is provided with a plurality of perforations 59, adapted to receive the rear pivot of the connecting link 51 to vary the length of the stroke of the feeding device, and while only two perforations 59 are shown in the drawings, any number may, of course, be employed.

40 In order to relieve the feeding device during its return movement of the weight of the stack, the latter is supported by a vertically movable stack supporting and charging device, which after the feeding device has returned to its initial position, lowers the stack to the bottom of the magazine and thereby arranges a charge of material in position to be operated on by the feeding device for forming the next bundle. Each

45 stack supporting and charging device consists of a follower and comprises in its construction a top horizontal supporting bar 60, and a central vertical slidable bar 61, operating in the groove of a vertical channeled bar or post 62, secured in its lower portion to the lower channeled bar 14. The vertical channeled bar or post 62 is provided at its lower portion with opposite ears or flanges 63, which are bolted or otherwise secured to the horizontal channeled bar 14, and the said bar or post 62 is arranged so that the bar 61 of the stack supporting and charging device is confined in the groove or channel of the said bar or post 62 by the bar 14.

50 The vertically movable stack supporting and charging devices are connected by links 64 with oscillatory arms 65 of a front transverse shaft 66, provided with a longitudinal groove or keyway 67 to receive keys for 70 slidably locking the arms 65 with the shaft 66, whereby when the auxiliary frames are adjusted laterally, the arms 65 will be carried with them in their adjustment. The arms 65 extend rearwardly from the rock 75 shaft 66 and the links 64 extend downwardly from the rear ends of the arms 65, and the channeled posts 62 are provided with vertical slots 68 through which pass lower pivots 69, which connect the links 64 with the 80 vertically slidable bars 61. The front transverse rock shaft extends across the space between the side channeled beam 3 and the intermediate longitudinal channeled beam 4, and is mounted in front bearing brackets 70, bolted or otherwise secured to the top flanges of the beams 3 and 4. These bearing brackets may be braced in any suitable manner if desired, and the transverse rock shaft is provided at its outer end with a depending 90 oscillatory arm 72, pivoted at its lower end to a block 73 having upper and lower openings 74 through which pass spaced upper and lower rods 75, extending forwardly from the front end 76 of a substantially horizontal 95 longitudinal bar or pitman 77. The rods 75, which are arranged in the same longitudinal plane as the bar or pitman 77, constitute an extension thereof and receive an adjustable block or abutment 78, arranged in spaced 100 relation with the front end 76 of the bar or pitman 77 and adapted to be positioned different distances therefrom to permit the bar or pitman to have a limited movement independently of the arm 72 of the rock shaft 105 for controlling the amount of movement imparted to the stack supporting and magazine charging device. The adjustable block 78 is provided with upper and lower openings 79 for the rods 75, and the outer portions thereof have screw threads 80 for the reception of nuts 81, arranged in pairs to form a lock for securing the block 78 in its adjustment.

110 The horizontally disposed longitudinal bar or pitman 77 is provided in its rear portion with a longitudinal slot 82 through which passes the main transverse shaft 53 forming a guide for the bar or pitman 77 and carrying a cam 83 for actuating the same. The rear end of the bar or pitman 77 is equipped with a roller 84, extending inwardly from the bar or pitman 77 and arranged to be engaged by the cam 83. The cam 83, which is keyed or otherwise fixed to the main transverse shaft 53, tapers inwardly toward the shaft and has similar uniformly curved side edges 85 and a curved outer edge 86, arranged concentric with the shaft 83 and adapted to cause the bar or pitman 77 to 115

120 125 130

- dwell at the end of its inward or rearward movement to maintain the stack supporting and charging device in an elevated position while the feeding device is being returned to its initial position. One of the curved side edges 85 contacts with the roller 84 and moves rearwardly the bar or pitman 77, while in its forward movement it is actuated by the weight of the material within the 5 magazine, the downward movement of the stack supporting and charging device and the consequent forward movement of the bar or pitman 77 being controlled by the other curved side edge 85 of the cam 83, which in 10 its rotary movement permits its stack to descend gradually to the bottom of the magazine.
- The upper and lower right and left hand threaded screws, which adjust the upper 20 and lower auxiliary frames and maintain the same in parallel relation and vary the length of the magazine, engage suitable nuts 86^a of the said auxiliary frames and are mounted at their ends in upper bearing 25 brackets 87 and in lower bearings 88 of the lower longitudinal beams 3 and 4 of the main frame. The upper bearing brackets are mounted on the upper longitudinal beam 11 of the main frame, and the lower bearings 30 88 extend from opposite faces of the webs of the beams 3 and 4. Upper and lower sprocket wheels 89 and 90 are mounted on the outer ends of the screws, which have reduced threaded inner terminals 91 receiving 35 nuts 92 and washers 93 interposed between the adjacent bearings and the nuts, which are adjustable to take up any end motion of the right and left hand threaded screws. The upper and lower sprocket wheels, which 40 receive the end thrust at the outer ends of the upper and lower adjusting screws, mesh with and are connected by a sprocket chain 94, which also meshes with a sprocket wheel 95 fixed to a rotary shaft 96, mounted in a 45 bearing opening in the outer front column of the main frame of the machine and provided at its inner end with a collar 97, keyed or otherwise secured to the inner end of the shaft 96. The sprocket wheel of the front 50 lower right and left hand threaded screw is located at a point in advance of the upper front sprocket wheel, and the sprocket chain, which extends downwardly from the upper front sprocket wheel, passes beneath 55 the sprocket wheel or pinion 95 and extends downwardly and forwardly at an inclination to the lower front sprocket wheel. The sprocket wheel 95 is arranged at a point intermediate of the shaft 96 and is located at 60 the outer face of the said column. The shaft 96 is provided at its outer end with a suitable operating device preferably consisting of a crank handle 98, adjustably secured in a transverse opening in the said shaft by 65 a set screw 99. The sprocket gear is adapt- ed to rotate simultaneously the right and left hand threaded screws, which move the upper and lower auxiliary frames laterally of the machine to space them and the mechanism carried by the frames the desired distance apart to suit the length of the material to be bundled. 70
- The cam wheel 58 is provided with an extended hub or sleeve 163, having a key 164 to engage a longitudinal groove or guide-way in the main transverse shaft 53 to slidably interlock the cam wheel 58 with the same. The cam wheel 58 of the lower auxiliary frames is adapted to slide along the main transverse shaft when the auxiliary 80 frames are adjusted laterally by the right and left hand threaded screws. 75
- The machine may be driven by any suitable power, which is connected by a belt with a pulley 267 loosely mounted on a transverse driving shaft 268, journaled in suitable bearings 269 of the main frame and carrying a pinion 270, which meshes with a gear wheel 148. The bearings 269 are preferably mounted on the longitudinal beams 90 2 and 4 of the main frame, and the pulley 267 is connected with the driving shaft by a clutch 271, which may be of any preferred construction. The clutch 271 is connected with a handle or lever 272, fixed to a longitudinal shaft 273, from which depends an arm 274 having a projecting point 275, which is carried into the path of a lug 276 of the gear 148 when the pulley is clutched to the driving shaft. The lug 276 100 is tapered to present a beveled engaging face, which is adapted to contact with the projecting point 275 of the arm 274 to throw the clutch automatically out of engagement with the driving wheel to stop the machine. 105 The depending arm 274 is detachably secured to the shaft by a set screw or other suitable means, and may be moved out of the path of the lug, and the handle or lever may be secured in position for holding the clutch in engagement with the pulley of the driving shaft when a continuous operation of the machine is desired. The shaft 273, which extends longitudinally of the machine, is journaled in suitable bearings of 110 the main frame and the operating handle or lever is fixed to the front end of the shaft 273 and is located at the front of the machine. The machine is equipped with an inclined skid 277, which extends downwardly at the back of the bundle receiving space or chamber and down which the bundles are adapted to slide. 115
- What is claimed is:—
1. A bundling machine comprising a vertical magazine adapted to hold a stack of material and provided at the lower portion with an opening, a bundle receiver located at said opening, a reciprocatory feeding mechanism movable backwardly and forwardly 120
  2. A bundling machine comprising a vertical magazine adapted to hold a stack of material and provided at the lower portion with an opening, a bundle receiver located at said opening, a reciprocatory feeding mechanism movable backwardly and forwardly 125
  3. A bundling machine comprising a vertical magazine adapted to hold a stack of material and provided at the lower portion with an opening, a bundle receiver located at said opening, a reciprocatory feeding mechanism movable backwardly and forwardly 130

wardly through the lower portion of the magazine for feeding a portion of the material from the bottom of the stack into said receiver to form a bundle, and means for holding the stack of material remaining in the magazine against displacement therein during the return movement of the feeding mechanism.

2. A bundling machine including means for holding a stack of material, feeding mechanism movable backwardly and forwardly for feeding a portion of the material from the bottom of the stack to form a bundle, and means for lowering the stack after the feeding means has returned to its initial position.

3. A bundling machine including a magazine adapted to hold a stack of material, feeding mechanism movable backwardly and forwardly through the magazine to feed the material from the bottom of the stack to form a bundle, and means for supporting the stack in an elevated position during the backward movement of the feeding means and for lowering the stack to the bottom of the magazine.

4. A bundling machine including a magazine adapted to hold a stack of material, feeding means movable backwardly and forwardly to feed the material from the bottom of the stack to form a bundle, and means movable upwardly and downwardly in the magazine for supporting the stack in an elevated position during the return movement of the feeding means and for lowering the stack to the bottom of the magazine after the feeding means has returned to its initial position.

5. A bundling machine including a magazine adapted to hold a stack of material and provided at the back with an opening, feeding means movable backwardly and forwardly through the lower portion of the magazine to feed the material from the bottom of the stack through the said opening to form a bundle, said feeding means being provided at the top with a support for holding the stack in an elevated position, and means for lowering the stack to the bottom of the magazine after the feeding means has returned to its initial position.

6. A bundling machine including a magazine adapted to hold a stack of material, reciprocatory feeding mechanism arranged to feed the material from the bottom of the stack to form a bundle and provided with a support for holding the stack in an elevated position, and means movable upwardly and downwardly in the magazine for supporting the stack in an elevated position while the feeding mechanism is moving backwardly and for lowering the stack to the bottom of the magazine after the feeding mechanism has returned to its initial position.

65 7. A bundling machine including a maga-

zine adapted to hold the material to be bundled, means for feeding the material from the bottom of the magazine to form a bundle, and a charging device movable upwardly and downwardly in the magazine for lowering the material to the bottom of the same.

8. A bundling machine including a magazine, means movable transversely of the magazine for feeding material from its contents to form a bundle, and a supporting and charging device for the contents movable in the magazine across the path of movement of the feeding means and adapted to support the contents in an elevated position on the separation of the bundle therefrom and lower said contents in the path of the feeding means when in normal position.

9. A bundling machine including a magazine provided at the bottom with an opening, feeding means movable backwardly and forwardly adapted to feed material from the bottom of the stack through the opening to form a bundle, and a vertically movable charging device provided with a support for holding the material in an elevated position in the magazine while the feeding means is moving backwardly, said charging device in its downward movement serving to lower the material to the bottom of the magazine.

10. A bundling machine including a magazine adapted to hold a stack of material, a feeding device movable backwardly and forwardly to feed the material from the bottom of the stack to form a bundle and provided at the top with means for supporting the stack in an elevated position during the forward movement of the feeding mechanism, and a charging device movable upwardly and downwardly within the magazine and provided with a support for holding the stack in an elevated position during the backward movement of the feeding mechanism and adapted in its downward movement to lower the stack to the bottom of the magazine to arrange the material in advance of the feeding mechanism.

11. A bundling machine including a magazine adapted to hold a stack of material, feeding mechanism comprising a slide, and means extending upwardly from the slide for feeding the material from the bottom of the stack to form a bundle, means for reciprocating the slide, and charging means movable upwardly and downwardly for supporting the stack in an elevated position and for lowering the same to the bottom of the magazine.

12. A bundling machine including a magazine adapted to hold a stack of material, reciprocatory feeding mechanism comprising a slide, a vertical bar mounted on and extending upwardly from the slide and adapted to engage and feed the material from the bottom of the stack, and a horizontal bar arranged at the top of and carried by

the vertical bar for supporting the stack in an elevated position, and charging means for lowering the stack to the bottom of the magazine.

5 13. A bundling machine including a magazine, feeding mechanism movable backwardly and forwardly for feeding the material from the bottom of the stack to form a bundle and adjustable upwardly and 10 downwardly to vary the size of the bundle, means for supporting the stack in an elevated position, and means for lowering the stack to the bottom of the magazine.

14. A bundling machine including a magazine adapted to hold a stack of material, 15 feeding mechanism movable backwardly and forwardly to feed the material from the bottom of the stack to form a bundle and comprising a slide, vertical bars adjustably secured to the slide for varying the size of the bundle, and a horizontal bar connecting the vertical bars and adapted to support the stack in an elevated position during the feeding movement, and charging means 20 movable upwardly and downwardly and adapted to support the stack in an elevated position while the feeding mechanism is moving backwardly and in its downward movement serving to lower the stack to the 25 bottom of the magazine.

15. A bundling machine including a magazine adapted to hold a stack of material and composed of spaced vertical sides, one of the sides or members being capable of 30 relative adjustment to vary the width of the space between them, feeding mechanism movable backwardly and forwardly for feeding material from the bottom of the stack to form a bundle, said feeding mechanism being adjustable upwardly and downwardly to vary the height of the bundle, and charging means for lowering the material to the bottom of the magazine.

16. A bundling machine including a magazine adapted to hold a stack of material 45 and provided with spaced front and rear vertical bars, the rear vertical bar terminating short of the bottom of the magazine to form an opening and being adjustable toward and from the front vertical bar to vary the width of the stack, feeding mechanism movable backwardly and forwardly to feed the material from the bottom of the stack through the said opening, and means for 50 lowering the stack to the bottom of the magazine.

17. A bundling machine including a magazine adapted to hold a stack of material, feeding mechanism movable backwardly and 60 forwardly to feed the material from the bottom of the stack to form a bundle, a stack supporting and charging device comprising a vertically movable follower provided at the top with a horizontal support adapted to 65 hold the stack in an elevated position, and

mechanism for actuating the feeding mechanism and for reciprocating the follower.

18. A bundling machine including a magazine, feeding mechanism movable backwardly and forwardly to feed the material 70 from the bottom of the magazine to form a bundle, guides for the feeding mechanism to permit the movement thereof to opposite sides of the magazine, a break jointed pivoted oscillatory lever connected with the feeding mechanism, and a rotary cam for 75 actuating the lever.

19. A bundling machine including a magazine, feeding mechanism movable backwardly and forwardly for feeding the material 80 from the bottom of the magazine to form a bundle, means for guiding the feeding mechanism to opposite sides of the magazine on the forward and backward travel of said mechanism, a rotary cam having a 85 groove, a lever pivoted at one end and provided at an intermediate point with means extending into the groove of the cam, whereby the lever is oscillated by the same, and a link connecting the other end of the lever 90 with the feeding mechanism.

20. A bundling machine including a magazine, reciprocatory feeding mechanism movable backwardly and forwardly to feed the material from the bottom of the magazine to form a bundle and having a slide, 95 means receiving the slide for guiding the feeding mechanism through and to opposite sides of said magazine, a cam located in rear of and below the plane of the magazine, a longitudinally disposed lever actuated by 100 the cam, and a pivoted link connecting the lever with the slide.

21. A bundling machine including a magazine adapted to hold a stack of material, 105 means for feeding the material from the bottom of the stack, a stack supporting and charging device movable upwardly and downwardly to support the stack in an elevated position and to lower the same to the 110 bottom of the magazine and consisting of a follower, a rock shaft having an arm connected with the follower, and cam actuated means for actuating the rock shaft.

22. A bundling machine including a magazine adapted to hold a stack of material, 115 mechanism for feeding the material from the bottom of the stack, means movable upwardly and downwardly in the magazine for supporting the stack in an elevated position and for lowering the stack to the bottom of the magazine, a rock shaft having an arm connected with the said means, an approximately horizontal pitman connected with the rock shaft, and a cam arranged to 120 actuate the pitman.

23. A bundling machine including a magazine adapted to hold a stack of material, mechanism for feeding the material from the bottom of the stack, means movable up- 125

- wardly and downwardly in the magazine for supporting the stack in an elevated position and for lowering the stack to the bottom of the magazine, a rock shaft having an arm connected with the said means, a shaft provided with a cam, and a pitman connected with the rock shaft and guided on the said shaft and having means coacting with the cam for actuating the pitman.
24. A bundling machine including a magazine adapted to hold a stack of material, mechanism for feeding the material from the bottom of the stack, charging means movable upwardly and downwardly in the magazine for supporting the stack in an elevated position and for lowering the stack to the bottom of the magazine, a pitman provided at an intermediate point with a slot, a shaft extending through the slot and forming a guide for the pitman, a cam mounted on the shaft, means carried by the pitman and engaged by the cam for actuating the pitman, and means for transmitting motion from the pitman to the charging means.
25. A bundling machine including a magazine adapted to hold a stack of material, mechanism for feeding the material from the bottom of the stack, a stack supporting and charging device movable upwardly and downwardly in the magazine, a rock shaft having an arm connected with the said means, a shaft having a cam, a pitman provided at an intermediate point with a slot receiving the shaft, and means carried by the pitman and arranged to be engaged by the cam for actuating the pitman.
26. A bundling machine including a magazine adapted to hold a stack of material, mechanism for feeding the material from the bottom of the stack, charging means movable upwardly and downwardly in the magazine for supporting the stack in an elevated position and for lowering the stack to the bottom of the magazine, a substantially horizontal reciprocatory bar or pitman, means arranged at one end of the bar or pitman for actuating the same, a block slidably mounted on the other end of the pitman to permit a limited independent movement of the pitman, and means connected with the block for transmitting motion from the reciprocatory bar or pitman to the charging means.
27. A bundling machine including a magazine adapted to hold a stack of material, mechanism for feeding the material from the bottom of the stack, a substantially horizontal reciprocatory bar or pitman provided at one end with spaced rods, means located at the other end of the bar or pitman for actuating the same, a block slidably mounted on the said rods, adjusting means for limiting the movement of the block, and means for transmitting motion from the block to the adjusting means.
28. A bundling machine including a magazine adapted to hold a stack of material, mechanism for feeding the material from the bottom of the stack, charging means consisting of a vertically movable follower operating in the magazine and adapted to support the stack in an elevated position and to lower the same to the bottom of the magazine, a rock shaft having an arm, a substantially horizontal reciprocatory bar or pitman provided at one end with spaced rods, a block slidably mounted on the rods and pivoted to the arm of the rock shaft, adjusting means carried by the rod for limiting the sliding movement of the block, means for transmitting motion from the rock shaft to the follower, and means for actuating the reciprocatory bar or pitman.
29. A bundling machine including a magazine, feeding mechanism movable backwardly and forwardly for feeding the material from the bottom of the stack, charging means consisting of a follower movable upwardly and downwardly in the magazine for supporting the stack in an elevated position and for lowering the same to the bottom of the magazine, an oscillatory lever connected with the feeding mechanism, a reciprocatory bar or pitman, means for transmitting motion from the pitman to the follower, a shaft forming a guide for the bar or pitman, and cams mounted on the shaft for actuating the bar or pitman and the said lever.
30. A bundling machine including a main frame, and auxiliary frames slidably mounted on the main frame and having spaced means forming a magazine, said auxiliary frames being adjustable toward and from each other to vary the length of the magazine.
31. A bundling machine including a main frame, auxiliary frames slidably mounted on the main frame and having spaced means forming a magazine, means carried by the auxiliary frames for feeding the material from the magazine, and means mounted on the main frame for adjusting the auxiliary frames to vary the length of the magazine.
32. A bundling machine including a main frame, spaced auxiliary frames adjustable toward and from each other and having spaced means forming a magazine, right and left hand threaded screws mounted on the main frame and connected with the auxiliary frames and adapted to adjust the means to vary the length of the magazine, and gearing for operating the adjusting screws.
33. A bundling machine including a main frame, laterally adjustable auxiliary frames slidably mounted on the main frame and provided with spaced means forming a mag-

- azine, upper and lower right and left hand threaded screws mounted on the main frame and connected with the auxiliary frames for moving the same toward and from each other to vary the length of the magazine, sprocket wheels fixed to the said screws, a sprocket chain arranged on the sprocket wheels, and operating mechanism including a sprocket wheel meshing with the sprocket chain for actuating the same to rotate the screws simultaneously. 34. A bundling machine including a main frame, upper and lower auxiliary frames slidably mounted on the main frame, spaced means carried by the upper and lower auxiliary frames and forming a magazine, and means for simultaneously adjusting the upper and lower auxiliary frames to vary the size of the magazine. 35. A bundling machine including a main frame, upper and lower auxiliary frames, the lower auxiliary frames being extended in advance of the upper auxiliary frames, spaced front and rear means mounted, respectively, on the lower and upper auxiliary frames and forming a magazine, and means for simultaneously adjusting the auxiliary frames toward and from each other to vary the size of the magazine. 36. A bundling machine including a main frame, upper and lower auxiliary frames mounted on the main frame, the lower auxiliary frames being extended in advance of the upper auxiliary frames, spaced means arranged at the front portions of the auxiliary frames and, carried by the same and forming a magazine and providing a rear opening at the bottom thereof, and means for adjusting the auxiliary frames to vary the size of the magazine. 37. A bundling machine including a main frame, upper and lower auxiliary frames, the lower auxiliary frames being extended in advance of the upper auxiliary frames, spaced means arranged at the front ends of the auxiliary frames and forming a magazine and providing a rear opening at the bottom thereof, said upper and lower frames being also spaced apart to provide a bundle receiving space or chamber in rear of the magazine, and means for adjusting the auxiliary frames to vary the size of the magazine. 38. A bundling machine including a main frame, upper and lower auxiliary frames mounted on the main frame, the lower auxiliary frames being extended in advance of the upper auxiliary frames, spaced vertical means arranged at the front ends of the upper and lower auxiliary frames and forming a magazine and providing an opening at the lower portion thereof, the spaced means of the upper frames being adjustable toward and from the spaced means of the lower frames to vary the width of the magazine, and means for adjusting the upper and lower auxiliary frames laterally to vary the length of the magazine. 39. A bundling machine including a main frame, laterally adjustable auxiliary frames having spaced means forming a magazine, means for adjusting the frames to vary the length of the magazine, mechanism mounted on the auxiliary frames for feeding the material from the magazine, a shaft mounted on the main frame, and means carried by the auxiliary frames and connected with the feeding mechanism for actuating the same and including rotary elements slidably connected with the said shaft. 40. A bundling machine including a main frame, auxiliary frames adjustably mounted on the main frame and having spaced means forming a magazine, means for adjusting the frames to vary the length of the magazine, feeding mechanism movable backwardly and forwardly for feeding the material from the magazine, a transverse shaft mounted on the main frame, oscillatory levers carried by the auxiliary frames and connected with the feeding mechanism, and cams also carried by the auxiliary frames and slidably mounted on the said shaft and actuating the said levers to operate the feeding mechanism. 41. A bundling machine including a main frame, laterally adjustable auxiliary frames having spaced means forming a magazine adapted to hold a stack of material, mechanism carried by the auxiliary frames for feeding the material from the bottom of the stack, stack supporting and charging means movable upwardly and downwardly in the magazine to support the stack in an elevated position and to lower the stack to the bottom of the magazine, a transverse rock shaft mounted on the main frame, means for actuating the rock shaft, and arms slidably interlocked with the rock shaft and connected with the stack supporting and charging means. 42. A bundling machine including a main frame, a magazine adapted to hold a stack of material, means for feeding the material from the bottom of the stack, stack supporting and charging means movable upwardly and downwardly for supporting the stack in an elevated position and for lowering the stack to the bottom of the magazine, mechanism for actuating the feeding means and the stack supporting and charging means and including a rotary element provided with a projecting lug, driving means, a clutch for connecting the driving means with the said mechanism, and clutch operated means having an arm arranged in the path of the lug and arranged to throw the clutch out of operation automatically.

43. A bundling machine including a magazine, means for feeding material from the magazine, mechanism for actuating the feeding means comprising a rotary element 5 having a projecting lug, driving means for actuating the said mechanism, a clutch for connecting the driving means with the said mechanism, and operating means for the clutch including an arm arranged in the 10 path of the lug and adapted to be actuated by the same to operate the clutch to disconnect the driving means from the said mechanism.
44. A bundling machine including means for holding a stack of material, feeding 15 mechanism movable through the lower portion of the magazine for feeding a portion of the material from the bottom of the stack to form a bundle, and means for lowering the stack to the bottom of the magazine to 20 recharge the machine.
45. A bundling machine including a magazine adapted to hold a stack of material, means for movement relative to the magazine for feeding the material from the stack, 25 and means movable at right angles to the first-named means for lowering the stack in the magazine.
46. A bundling machine comprising a 30 magazine adapted to hold a stack of material, a feeding device movable backwardly and forwardly at the bottom of the magazine to opposite sides thereof for feeding the material from the bottom of the stack to form a bundle, and means for holding the 35 remainder of the stack in elevated position during backward movement of said device, said feeding device being provided with a support for holding the remainder of the stack in an elevated position during the 40 forward movement of said device.
47. A bundling machine including a main frame, auxiliary frames slidably mounted on the main frame, right and left hand threaded screws mounted on the main frame 45 and connected with the auxiliary frames for moving the same toward and from each other, and means for rotating the screws.
48. A bundling machine including a main frame, auxiliary frames slidably mounted 50 on the main frame, right and left hand threaded screws mounted on the main frame and connected with the auxiliary frames, sprocket wheels connected with the screws, a sprocket chain arranged on the sprocket 55 wheels, and operating mechanism including a sprocket wheel meshing with the sprocket chains for actuating the same to rotate the same simultaneously.
49. A bundling machine including a main 60 frame, upper and lower auxiliary frames slidably mounted on the main frame and movable toward and from each other, upper and lower right and left hand threaded screws mounted on the main frame and connected with the upper and lower auxiliary 65 frames, and gearing for simultaneously rotating the screws for sliding the auxiliary frames toward and from each other.
50. A bundling machine comprising a magazine and mechanism for taking a quantity of the contents of said magazine and for retaining the remainder of said contents therein on the discharge of the quantity of material in bundle form therefrom. 70
51. A machine of the character described, 75 comprising a magazine for holding material, a bundle receiver located at one side of the magazine, and feeding mechanism movable transversely of the magazine for the feeding of a portion of the material therefrom to the receiver to form a bundle, and also for holding the remainder of the material in the magazine against displacement and out of the path of said feeding mechanism while active for the delivering of the bundle. 80
52. A bundling machine comprising a 85 magazine, means movable through the magazine for feeding material therefrom to form a bundle, and a device movable toward and away from the magazine for delivering material to the feeding means and adapted to support the contents elevated above the path of movement of the feeding means during the delivering of the material. 90
53. A bundling machine comprising a 95 magazine, feeder means movable for delivering a bundle of material from the magazine, means operative with the feeder means to sustain the remainder of the contents of the magazine therein on the delivering action of said feeder means, and means for lowering the contents of the magazine into the path of the feeder means when in normal position. 100
54. A bundling machine comprising mechanism for delivering a bundle of material, means on the delivering means to sustain material from the delivering action of said first-named means when active for discharging a bundle, means for lowering the 105 material into the path of the delivering means when in normal position, and means for imparting reciprocating movement to the delivery means for moving the same to normal and delivering positions. 110
55. A bundling machine comprising a 115 magazine, means for transferring part of the contents of the magazine therefrom to a point to form a bundle, means operative with the transferring means to sustain the remainder of the contents within the magazine on the delivering action of said transferring means, means for lowering the contents of the magazine into the path of the transferring means when in normal position, means for reciprocating the transferring means to shift the same to delivering and normal positions, and means coactive with the last-named means for imparting movement to the lowering means. 120
- 125
- 130

56. A bundling machine having means for bundling material therein, means carried by the first-named means for holding the material separated from the bundle when being delivered, and means for feeding the material to the bundling means subsequent to the delivery of a bundle thereby. 5
57. A bundling machine comprising a magazine, means for delivering a bundle from said magazine, means carried by said first-named means for holding the contents of the magazine separated from the bundle when being delivered, means for feeding the contents to the bundle delivering means subsequent to the delivering of a bundle therefrom, means for varying the size of the bundle to be delivered by the delivering means, and means for varying the capacity of the magazine. 10
58. A bundling machine comprising a magazine, means for delivering a bundle from said magazine, means carried by said first-named means for holding the contents of the magazine separated from the bundle when being delivered, means for feeding the contents to the bundle delivering means subsequent to the delivering of a bundle therefrom, means for varying the size of the bundle to be delivered by the delivering means, means for varying the capacity of the magazine, and means for receiving the bundle from the delivering means. 15
59. A bundling machine comprising a magazine, means for delivering a bundle from said magazine, means carried by said first-named means for holding the contents of the magazine separated from the bundle when being delivered, means for feeding the contents to the bundle delivering means subsequent to the delivering of a bundle therefrom, means for varying the size of the bundle to be delivered by the delivering means, means for varying the capacity of the magazine, means for receiving the bundle from the delivering means, and mechanism for successively operating the bundle delivering means and the contents feeding means. 20
60. A bundling machine, comprising feeding mechanism for the delivery of a bundle of material, means for supplying material to the feeding mechanism, and means for controlling the supply of material and adapted to automatically bring the supply into position for the feeding mechanism to deliver a bundle of said material from the supply by said mechanism, and means for shutting off the supply of material to the feeding mechanism when a bundle from the supply has been received thereby and delivered, and mechanism for imparting movement to the feeding mechanism and also for varying the throw thereof. 25
61. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, and means for shutting off the supply of material to the feeding mechanism when a bundle from the supply has been received thereby and delivered. 30
62. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, means for shutting off the supply of material to the feeding mechanism when a bundle from the supply has been received thereby and delivered, and mechanism for imparting movement to the feeding mechanism and also for varying the throw thereof. 35
63. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, means for shutting off the supply of material to the feeding mechanism when a bundle from the supply has been received thereby and delivered, mechanism for imparting movement to the feeding mechanism and also for varying the throw thereof, and means for varying the size of the bundle to be delivered by the feeding mechanism. 40
64. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, means for shutting off the supply of material to the feeding mechanism when a bundle from the supply has been received thereby and delivered, mechanism for imparting movement to the feeding mechanism and also for varying the throw thereof, and means for varying the size of the bundle to be delivered by the feeding mechanism. 45
65. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, means for shutting off the supply of material to the feeding mechanism when a bundle from the supply has been received thereby and delivered, mechanism for imparting movement to the feeding mechanism and also for varying the throw thereof, and means for varying the size of the bundle to be delivered by the feeding mechanism. 50
66. A bundling machine, comprising feeding mechanism for the delivery of a bundle of material, means for supplying material to the feeding mechanism, means for controlling the supply of material and adapted to automatically bring the supply into position for the feeding mechanism to deliver a bundle of said material from the supply by said mechanism, means for shutting off the supply of material to the feeding mechanism when a bundle from the supply has been received thereby and delivered, mechanism for imparting movement to the feeding mechanism and also for varying the throw thereof, and means for varying the size of the bundle to be delivered by the feeding mechanism. 55

In testimony, that I claim the foregoing as my own, I have hereto affixed my signature in the presence of two witnesses.

JAMES M. LEAVER, JR.
